UNITED STATES PATENT OFFICE.

PATRICK H. FAY, OF JANEVILLE, WISCONSIN, ASSIGNOR OF ONE-TENTH TO MARY ELLEN STANTON, OF JANEVILLE, WISCONSIN.

TOY.

1,248,639.

Specification of Letters Patent.

Patented Dec. 4, 1917.

Application filed February 27, 1917. Serial No. 151,339.

To all whom it may concern:

Be it known that I, PATRICK H. FAY, a citizen of the United States, residing at Janesville, in the county of Rock and State 5 of Wisconsin, have invented certain new and useful Improvements in Toys; and I do hereby declare the following to be a full, clear, and exact description of the invention, such as will enable others skilled in the art 10 to which it appertains to make and use the same.

This invention relates to toys, and particularly to a toy whose use partakes of the nature of a game.

15 The object of the invention is to produce a figure toy which may be placed in upright position upon a suitable supporting surface, and used as a target at which a ball may be thrown or bounced, an opening in the 20 toy being adapted to receive an accurately directed ball. In connection with this invention, it is also an object to provide a receiving receptacle into which the ball may drop, and then falling upon a movable plat- 25 form will cause the descent of the latter until the ball appears opposite a second opening through which it may return to the player. In order to add to the interest of the game, the ball or figure may simulate 30 the form of a caricatured human figure and may carry a pair of pivoted arms, which will swing outwardly by a mechanism connected to the platform when the ball drops upon the latter, this outward swinging of 35 the arms serving to characterize a "hit."

With the above objects in view and such others as may hereinafter appear, my invention will now be fully set forth and described, reference being had to the accompa- 40 nying drawings.

In the drawings:—

Figure 1 is a front elevation,

Fig. 2 is a rear elevation,

Fig. 3 is a side view, and

45 Fig. 4 is a section on line 4—4 of Fig. 2.

Referring more particularly to the drawings, 1 represents a board or plate of suitable material which is shaped into the form of a caricatured human being, as indicated, 50 or may be of any other suitable conformation which will accord with the idea of a combined toy and game. The board is provided with a foldable easel support 2, which, in the present instance, is a shaped wire length hinged to the upper portion of the 55 back of the figure 1. At a point which coincides with the mouth of the figure, the latter is provided with an opening 3 which is of suitable size to permit the projection therethrough of a rubber ball or other suitable missile and at a lower point, the figure is provided with a second opening 4 through which the ball may be returned or ejected. Secured to the back of the figure 1 in hinged relation thereto, is a set of vertical 60 bars 5 which are provided at their upper and lower ends with the looped connecting arms 6, the looped ends thereof being passed through eyelets 7 entered into the figure above the upper opening 3 and below the 65 lower opening 4. Also hinged to the board between the openings is a horizontal yoke or frame 8 which is mounted in the eyelets 9. The yoke is formed of a wire strand and has its ends downturned as at 10, so that 70 while it may be folded upwardly against the figure, the extensions 10 will cause the yoke or frame to be normally positioned in horizontal relation to the figure when it is unfolded. The yoke 8 is provided with the 75 recesses or notches 11 which correspond in number to the vertical bars 5 and receive the latter when the frame and bars are both extended, so that the interlocking elements 80 form a frame work behind the figure which 85 catches and retains the ball as it comes through the upper opening 3, and drops toward the lower opening 4. Mounted within the cage provided by the frame and bars is a vertically movable element 12 which is pref- 90 erably shaped from a wire length and has vertical legs which are slidable in the guide eyes 13 and at its lower end is bent outwardly and upwardly to form a platform or basket upon which the ball may drop, a 95 sheet of material 14 being mounted upon the basket in order to increase its extent and also to provide an incline which will turn the ball forwardly, so that as the platform is carried downwardly by the ball, the 100 latter may roll out of the opening 4 as soon as the latter has reached a low enough level. It will be noted that the vertical legs of the element 12 lie on opposite sides of the opening 4 so that they do not interfere with the 105 ejection of the ball when the latter reaches its lower limit. The upper ends of the element 12 are pivotally connected to the links 15 which in turn are pivoted upon the inner 110 ends of arms or levers 16 which are pivoted

to the back of Fig. 1, and as viewed from the front simulate the shape and action of arms for the figure, the downward movement of the platform causing the arms to be thrown outwardly, and the arms being also of sufficient weight to act as returning devices for the platform as they drop.

From the foregoing, it will be evident that the device may be used as a simple toy, or 10 may be used as a game, whose object is to develop accuracy as well as an interest. It is simply constructed, and by reason of the foldable nature of the supporting devices and the cage members, may be readily 15 folded and stored when not in use.

What I claim as my invention is:—

1. A combined toy and game comprising in combination, a figure adapted to be supported in vertical relation, and having upper 20 and lower openings formed therein, a foldable cage hinged to the back of the figure and covering said openings, a platform slidably carried upon the back of the figure, and normally positioned between the openings, 25 and adapted to be carried downwardly to eject a ball through the lower opening, and means for returning the platform to its elevated position.

2. A combined toy and game comprising 30 in combination, a figure adapted to be supported in vertical relation, and having upper and lower openings formed therein, a foldable cage hinged to the back of the figure and covering said openings, a platform 35 slidably carried upon the back of the figure, and normally positioned between the openings and adapted to be carried downwardly to eject a ball through the lower opening, and arms pivoted upon the figure and connected to said platform, said arms swinging 40 outwardly when the platform is carried.

downwardly by the weight of a ball, and serving to return the platform when the ball is ejected.

3. A combined toy and game comprising 45 in combination, a figure adapted to be stood in vertical position and having upper and lower openings formed therein, a series of vertical bars hinged to the rear of the figure over said openings, means for locking said 50 bars into a cage, a slidable element mounted upon the back of the figure between the openings, a platform carried by said element and adapted to receive a ball and carry it downwardly to be ejected through the 55 lower opening, and arms pivoted upon the rear of the figure and connected to the slid- 60 able element, said arms being thrown outwardly when the platform descends and returning the platform to elevated position when the ball is ejected from the platform.

4. A combined toy and game, comprising in combination, a figure adapted to be supported in vertical relation, and having upper and lower openings formed therein, and a 65 foldable cage on the back of the figure and inclosing the openings to guide a ball from the upper to the lower opening.

5. A combined toy and game, comprising 70 in combination, a figure adapted to be sup- 75 ported in vertical relation, and having upper and lower openings formed therein and a slid- 80 able platform mounted on the back of the figure and positioned to receive a ball passed through the upper opening and de- liver it through the lower opening.

In testimony whereof, I affix my signature, in the presence of two witnesses.
